WARE

METHOD FOR PRODUCING WATER GAS

Application filed September 21, 1921. Serial No. 502,141.

This invention relates to a method for producing water gas from pulverized carbonaceous material, usually coal.

Methods of producing gas from hard coal by burning with an insufficient supply of oxygen to form CO are well known and many different types of apparatus have been devised for this purpose. Following the same principle of operation, pulverized coal has been employed for producing gas by blasting the coal into a chamber where it is burned to form CO₂ which is then reduced to CO by admitting an additional supply of coal.

In contradistinction to these methods, the invention provides primarily a method of obtaining gas from pulverized carbonaceous material, particularly pulverized coal, by destructive distillation of the material while the particles are in a state of suspension resulting in the complete gasification of the material. Where the destructive distillation is carried on in the presence of steam, not only is the gas resulting from distillation produced, but the steam is broken up into hydrogen and oxygen, the latter uniting with free carbon to form carbon monoxide, and the hydrogen escaping as free hydrogen or in the form of hydrocarbons. The gas produced may be enriched by the addition of heavy hydrocarbons such as oil or tar.

Preferably the method described of gasifying carbonaceous material is carried on in an externally heated retort alone, or in the presence of steam or hydrocarbon enriching agents, or both. The material should be injected into the retort in such manner as to cause the particles of material to be separated in suspension within the retort in the form of a sheet of great expanse. One way to accomplish this result is by feeding the material into a blast of steam together with oil or tar, where an enriching agent is employed, in which case the atomized steam and oil or tar combine with the particles of material to form a fine spray temporarily suspended in the retort and gradually descending under the action of gravity toward the bottom thereof. The best results are secured in a chamber of long and narrow construction so that the heat radiated from the walls thereof will im-

mediately penetrate the material upon its entrance into the retort thus causing the destructive distillation to begin at once and to be completed before the descending particles formed into a thin sheet of great expanse between these walls reach the bottom of the retort. This will readily be accomplished particularly where the retort is of substantial height and the material is introduced near the top thereof. Also under these conditions the atomized steam will at once break up into hydrogen and oxygen and the latter will unite with free or fixed carbon to form water gas.

The gas produced is subjected to a cooling and washing process in the usual manner wherein the solid and liquid matter contained in the gaseous constituents will be removed and the tar returned to the retort for permanent fixation as an enriching gas.

In carrying out the method and variations thereof above described, one form of apparatus employed is a type having a retort which is heated by a pulverized fuel fired furnace. This type of apparatus includes a retort, into which the pulverized material to be gasified is injected, a fuel chamber and a flue for conducting hot gases to the retort, the fuel chamber preferably being located beneath the retort and having a plurality of vertically extending flues for conducting the hot gases therefrom to externally heat the walls of the retort. Irrespective of the particular form or arrangement of the parts of the apparatus for heating the retort, the means for injecting the material into the retort may comprise a conveyor, a nozzle, and means for injecting steam together with tar or oil, or both, through the nozzle by which the material is carried from the conveyor by injector action of the steam or mixture of steam and tar or oil and propelled by the latter into the retort in the form of a sheet.

Another form of apparatus is one which, instead of using pulverized fuel as a source of heat, as in the above example, is designed for employing a portion of the gas produced by the apparatus for heating the retort thereof. In this construction, the retort for gasifying coal has adjacent its enclosing walls

a plurality of flues for externally heating the retort, and these flues are provided with means for employing a portion of the gas produced in the retort for heating the latter. Preferably the flues are arranged on opposite sides of the retort, each flue consisting of a pair of passage-ways, one being a gas up-take passage-way and the other a gas down-take passage-way, and a burner is provided for each of the flues positioned in the gas up-take passage-way. These burners have connection with suitable means for supplying thereto a portion of the gas produced by the apparatus.

For a better understanding of the details of the invention reference may be had to the accompanying drawings illustrating one form of apparatus for practicing the method of the invention.

In the drawings

Fig. 1 is a sectional view in elevation of a gas generating apparatus for pulverized carbonaceous material in which pulverized fuel is employed for heating the retort where-
in the pulverized material is gasified; and

Fig. 2 is a cross sectional view of the gas generating apparatus illustrated in Fig. 1 taken along the line 2—2 of Fig. 1.

Referring to Figs. 1 and 2, illustrating the pulverized coal fired type of gas generating apparatus, the apparatus is built of suitable brick, the end walls 6 being of heavy construction joined by top and bottom walls 7 and 8 respectively, and heavily constructed side walls 9 enclosing an inner chamber in which are the retort 10 and the combustion chamber 11 separated by an arch 12. The retort 10 is a long and narrow chamber situated in the upper part of the apparatus and extending from end to end thereof, being formed by side walls 13 and upper and lower arches 14 and 12 respectively. Each of the end enclosing walls 6 has near the top wall 7 a port 15 opening into an inwardly flaring recess 16. Fitting in the port 15 is a nozzle 17 disposed substantially horizontally as shown and having a Y-connection with a steam pipe 18 and a pipe 19 through which vaporized tar is conducted. Also opening into the recess 16 is the discharge end of an inclined screw conveyor 20 for conveying the pulverized carbonaceous material from a bin (not shown) to the retort. The top wall 7 is provided with a series of gas outlet openings 21 through which the gas produced in the retort 10 is conducted to pipe lines for ultimate discharge after the washing treatment to a holder.

Situated beneath the retort 10 is a combustion chamber 11 designed for burning pulverized fuel which is injected into the combustion chamber by means of an induction burner 22. Situated between the side walls 13 of the retort and the walls 9 of the apparatus is a plurality of vertical flues 23

communicating at one end with the combustion chamber 11 through flaring openings 24 in the arch 12, and at the other end with a pair of waste gas flues 25 formed in the top and side walls 7 and 9, extending longitudinally of the apparatus and connecting with means for leading out waste gases. Slidably mounted in each of the side walls 9 are dampers 26, one for each flue, which may be regulated to close any or all of the flues to the passage of gases, the dampers in their closed position fitting into recesses 27 in the side walls 13 of the retort.

With the arrangement described, it will be seen that the retort 10 confines the pulverized coal and steam in the form of a thin, vertical sheet of great expanse and heat is applied to the sheet through the opposite side walls 13 and through the bottom wall 12. By this method of application of the heat all of the coal particles introduced into the chamber are heated substantially uniformly and the insulating effect present in retorts in which the mass being heated is of considerable thickness is largely eliminated. With the present arrangement the heat is applied over a large area and the mass of material being heated is relatively thin so that the heat reaches the particles throughout the mass.

The heat applied at the lower edge of the retort insures the complete distillation of particles which may settle on the lower wall.

It will be noted that the pulverized coal, steam and enriching agent, when the latter is used, are all introduced substantially horizontally into the high narrow chamber near the top thereof and beneficial results are derived from this manner of feeding. One of the advantages obtained is that the stream of steam and coal entering the chamber at a substantial velocity through the recess 16 expands when it enters the chamber with a resultant decrease in velocity. The stream spreads so as to fill evenly the space defined by the hot side walls, and there is a change in direction in the flow of the particles which float gently downwardly remaining in suspension for a period of time sufficient to permit substantial completion of the distillation and chemical reactions which occur.

The withdrawal of the gas at the top insures a flow of gas and solids in opposite directions through the chamber, the solids slowly descending to the hot floor where the process may be finished as to such particles as have not taken their full part in the reactions while in suspension. The upward flow of the gas assists in suspending the solid particles in the manner described, and it is preferable to adjust the rate of admission to the progress of the reaction so that gasification of the particles is substantially complete while they are in suspension.

The operation of the apparatus thus described is as follows: The pulverized mate-

rial to be gasified, as for instance pulverized coal, is conducted to the retort chamber 10 from a bin by means of the screw conveyor 20, the material being led to a point in the recess 16 adjacent the discharge end of the nozzle. The mixture of superheated steam conducted through the pipe 18 and vaporized tar or oil, which is preferably preheated and conducted through the pipe 19, is discharged from the nozzle 15 at high velocity producing an injector action and drawing the pulverized material from the end flights of the screw conveyor near its discharged end by suction, the blast of steam and vaporized tar then propelling the material into the retort in the form of a sheet of great expanse defined by the closely spaced walls 13 of large area. Since the discharging means for coal and the mixture of steam and tar or oil are situated in the upper part of the retort 10 near the top wall 7, the sheet of suspended material intermixed with steam and atomized hydrocarbons slowly descends by gravity toward the bottom of the chamber. Immediately the material is injected into the retort, and continuously during its descent, the suspended particles are subjected to an intense heat radiated from the externally heated walls of the retort chamber so that destructive distillation of the material begins at the instant of its introduction into the chamber, proceeds as the material descends and is substantially completed before it reaches the bottom of the retort. Where pulverized coal is employed, the destructive distillation results in coal gas, the volatile constituents of the coal being separated from the fixed carbon content. The walls of the retort chamber are heated to a temperature of 2800° to 3000° F. at which temperature the destructive distillation is rapidly completed and the steam substantially dissociated in the presence of incandescent carbon into hydrogen and oxygen, the latter combining with the fixed or free carbon of the coal to produce carbon monoxide, and the hydrogen escaping as free hydrogen or in the form of hydrocarbons. The water gas thus produced passes out of the ports 21 and into pipe lines through a washer 50 to the gas holders. The tar recovered during the cooling and washing is returned to the supply system and again injected into the retort through the pipe 19. Upon its second entrance into the retort the tar is broken up and gasified, and serves to enrich the gas, the enrichment being sufficient to bring the gas up to the usual calorific standard. Additional enrichment may, of course, be produced by admitting oil with the tar.

Should it prove necessary or desirable to provide means for the removal of ash or other ungasified substances which might collect upon the bottom of the retort chamber 10, a clean-out door or gate 29 at either or both

ends as shown in Figs. 1 and 2 may be provided.

The combustion chamber 11 is of large dimensions as is customary in pulverized fuel-fired furnaces. The hot gases from the combustion chamber pass upwardly through the flues 23 adjacent the side walls 13 of the retort and through the waste gas flues 25, and thus the enclosing walls 12 and 13 of the retort are, at their outer surfaces, in direct contact with the hot gases of combustion from the chamber 11, the wall or arch 12 separating the combustion chamber from the retort. The combustion chamber 11 is provided with a cleanout door 28 for the purpose of removing ash and non-combustible material deposited on the bottom of the chamber.

I claim:

1. The method of producing water gas, which comprises maintaining a quantity of pulverized coal and steam in intimate mixture in suspension in the form of a relatively thin, vertical sheet of great expanse by continuously supplying pulverized coal and steam to the sheet near the top thereof, and distilling the coal while in suspension and substantially dissociating the steam into its component elements in the presence of incandescent particles of the coal by the application of heat to both faces and along the bottom edge of the sheet.

2. The method of producing water gas, which comprises maintaining a quantity of pulverized coal and steam in intimate mixture in suspension in the form of a relatively thin vertical sheet of great expanse by continuously supplying pulverized coal and steam to the sheet near the top thereof, applying heat to the opposite faces and the bottom edge of the sheet in amounts sufficient to render the coal incandescent and to effect substantial dissociation of the steam into its component elements as well as the destructive distillation of the coal while the particles thereof are in suspension, and continuously injecting an enriching material into the mixture of coal and steam in suspension.

3. The method of producing water gas, which comprises continuously introducing pulverized carbonaceous material and steam in a substantially horizontal direction into a high, narrow, long vertically disposed chamber near the top thereof, the solid material and steam forming a relatively thin vertical sheet within the chamber through which the particles of the material descend slowly by gravity, heating the sheet of material and steam to a temperature sufficient to effect the water gas reaction, and completing the water gas reaction with respect to particles of material which descend to the bottom of the chamber by heat transferred through said bottom.

4. The method of producing water gas, which comprises introducing pulverized fuel

and steam substantially horizontally into a high, narrow, long chamber having walls of great expanse near the top of said chamber to form a relatively thin vertical sheet of said solid material and steam within the chamber through which the solid particles slowly descend by gravity, the particles losing velocity shortly after they enter the chamber and changing direction before their descent, and supplying heat to both faces of the sheet sufficient to effect the water gas reaction.

5. The method of producing water gas, which comprises continuously introducing pulverized carbonaceous material and steam in a substantially horizontal direction into a high, narrow, long, vertically disposed chamber, near the top thereof, heating the walls of the chamber to a temperature of at least 2800° F., the solid material and the steam forming a relatively thin sheet within the chamber, through which the particles of the material descend slowly by gravity and thereby heating the sheet of material and steam to effect the water gas reaction.

25 6. The method of producing water gas, which comprises continuously introducing pulverized fuel and steam in a substantially horizontal direction into a high, narrow, long, vertically disposed chamber, near the top thereof, the solid material and the steam forming a relatively thin sheet within the chamber through which the particles of the material descend slowly by gravity, and heating the sheet of material and steam to a temperature of approximately 2800° F. to 3000° F. to effect the water gas reaction.

7. The method of producing water gas which comprises continuously introducing pulverized fuel and steam in a substantially horizontal direction into a high, narrow, long, vertically disposed chamber, near the top thereof, the solid material and the steam forming a relatively thin sheet within the chamber through which the particles of the material descend slowly by gravity, and heating the sheet of material and steam to a temperature sufficient to effect a substantial water gas reaction and producing essentially carbon monoxide and hydrogen.

50 In testimony whereof I affix my signature.
SYDNEY JOHN McAULIFFE.
